UNITED STATES PATENT OFFICE.

CLARKSON A. DISBROW, OF NEW ROCHELLE, NEW YORK, AND WILLIAM E. GADD, OF PHILADELPHIA, PENNSYLVANIA, ASSIGNEES TO THE RAIL JOINT COMPANY, OF NEW YORK, N. Y., A CORPORATION OF NEW YORK.

TRACK-LINING DEVICE.

Application filed January 16, 1925. Serial No. 2,914.

This invention relates to track lining devices which are adapted for laterally shifting the rails of a track to proper alignment without materially disturbing the ballast; 5 and without disturbing the track fastenings.

The re-lining of railroad tracks frequently presents difficulties in effecting the proper seating of the lining device, principally on account of the character and amount of ballast employed. Heretofore if the ballast level was close to the rails, it was difficult to position the lining device under a given rail without first removing a large quantity of the ballast.

Accordingly, one of the objects of my invention is to provide a track lining device which may readily be successfully positioned and operated, although the positioning is confronted with the condition above noted.

Another object of the invention lies in the provision of a ballast engaging anchor which is pivotally connected to the fulcrum plate of the rail-shifting lever, whereby said fulcrum plate may easily be positioned under a rail, and whereby said plate when so positioned will be automatically secured against outward movement by the pivoted anchor during the lateral shifting of the rail.

A further object is to provide the said anchor with a hand grip whereby the lining device may be readily removed from its operative position and transported to another point of work.

With these and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a sectional view showing the application of my invention.

Figure 2 is an enlarged detailed side elevation of the track-lining device showing the ballast-engaging anchor in position to permit of the ready insertion of the device under a rail.

Figure 3 is an enlarged detail top plan view of the device, and

Figure 4 is a top plan view of the earth-engaging anchor.

Figures 5 and 6 are a plan and edge view 55 respectively of a primary form of the invention.

Similar reference characters designate corresponding parts throughout the several figures of the drawings. 60

In its general organization, the present track lining device includes a base or fulcrum plate A having a forwardly located anchoring element B pivotally connected thereto, a rail-bearing or shifting lever C, 65 and an operating lever D.

Referring to the details of construction, the base A consists of a relatively flat body 5 which preferably is formed of either malleable iron or pressed steel. The base at its forward or inner end preferably is provided with a pair of spaced bearing arms 6—6 which extend longitudinally and project downwardly below the general plane of said base. These bearing arms are formed with 70 transversely disposed aligned bearings for receiving a bearing pin 7, the pin extending beyond the outer faces of the arms and across the space between said arms. The base A is furthermore provided on its upper face 75 with a plurality of bearing seats 8 for the pivot nose 8^a of the actuating cam to be presently referred to, these seats being formed in a longitudinal series.

The rail-bearing or shifting lever C has 85 its inner end usually disposed between the bearing arms 6—6 and fulcrumed on the transverse bearing pin 7. This lever usually is offset at its forward end as indicated at 9 to dispose the parts of the liner in proper operative relation to each other and to the rail R. By reason of the offset portion 9, the lever proper is permitted to lie flat against the seats 8 when said lever is in its inoperative position, thus making a device 90 which is very compact, and consequently occupies but little space during transportation or storage.

The ballast-engaging anchoring element B is in the nature of a lever, one end 11 100 being of spade-like outline and having a centrally disposed pointed end 12 for engagement with and in the ballast, and the other end 13 constituting a rock-arm for

use in engaging and disengaging the element respectively in and from the ballast. This anchoring element is preferably formed with a pair of transversely disposed spaced bearings 14—14, and intermediate these bearings the element is formed with an opening 15. The opening 15 receives the bearing arms 6—6 and the fulcrum end of the operating lever C, and the bearings 14—14 are engaged with the outer ends of the bearing pin 7. Thus the anchoring element B is pivoted on the inner end of the fulcrum plate A, the pointed end 12 of said anchoring element normally projecting towards the outer end of the fulcrum plate. By reason of the fulcrum 7 being disposed in a plane slightly below the general plane of the fulcrum plate, the ballast-engaging end of the anchor B may be disposed in substantial parallelism with said plate, thus further providing a decidedly compact arrangement. The extreme outer end of the anchor element B is preferably curved downwardly to the point 12, whereas the other end or rock-arm 13 of said anchor element is normally extended upwardly at an inclination. The rock-arm 13 is preferably formed with one or more longitudinally disposed socketed enlargements 16 adapted to receive one end of a crowbar or other suitable tool, and the arm is furthermore provided with an opening 17 forming a resultant hand grip for the device. It will thus be seen that the ballast engaging anchor is selfadjusting and is pivotally connected with the fulcrum plate 7 independently of the rail shifting lever. The operating lever or crow-bar D is fitted to the rocking cam 18 which is adapted to be successively fulcrumed at its end or nose 8^a against the bearing shoulders 8 which are formed on the upper face of the base A.

In operation, the base A together with the anchor B and rail-engaging lever C are pushed under the rail R, the parts being in normal or in operative positions as shown in Figure 2. Thus the device may be readily positioned under a rail although the ballast level is fairly close to said rail. The device is inserted under the rail until the fulcrum end of the rail-engaging lever C is well under said rail. The operating lever D is then positioned on the base A and the cam 18 is engaged with the under face of the rail-bearing lever C.

The lever D is then actuated, the lever C engaging the base flange of the rail. During the initial operation, the tendency is for the base plate A to be moved outwardly under the influence of the levers C and D, but the pivoted ballast-engaging element B will, through its downwardly curved point 12, automatically seat itself in the ballast and thereby limit such outward movement of the base plate A. By reason of the rail-

engaging lever C being fulcrumed at the inner end of the base plate, a downward thrust on said inner end will occur upon application of the operating lever D, and this downward thrust of the inner end of the base plate will be transferred to the pivoted anchor B, thus causing the latter to be forced downwardly into firm engagement with the ballast and thereby prevent any further outward movement of the base plate A. The operating lever D is then shifted successively against the seats 8 until the rail has been shifted laterally into proper alignment.

A crow-bar can be inserted in the socket 16 of the anchor element B to facilitate loosening thereof. Upon oscillatory movements of the crow-bar as thus positioned, the anchor element B may be easily released from its tight engagement with the ballast, and then upon grasping the hand grip 17 the device may be readily withdrawn from its former operative position and transferred to another point of work. It will be noted that the liner may also be initially positioned under the rail by grasping the hand grip 17 with the anchor folded and drawing the whole device into place. Also the socketed enlargements 16 present foot-holds for pressing downward with the foot on the anchor, as with a spade, to assist in sinking it into the ballast.

In order to illustrate the development of the invention there is shown in Figures 5 and 6 of the drawings a primary form thereof. That form of invention includes the base or fulcrum plate A having at its downturned end portion 17 a pivotally mounted anchor element 18 preferably formed above its pivotal or hinge point 19 with an enlarged double-beveled head member 20 which may be conveniently engaged by the foot of the operator to facilitate thrusting the anchor point or blade into the ballast. The pivotal mounting of the anchor element 18 is such as to permit the same to have a folding action, thereby facilitating the sliding of the base plate into position over the ballast and under or adjacent the rail.

Without further description it is thought that the features and advantages of the present invention will be readily apparent and it is of course understood that changes in the form, proportion and minor details of construction may be resorted to without departing from the spirit or scope of the appended claims.

I claim:

1. A track lining device including a base, and a ballast-engaging anchor pivotally connected to one end of said base, the outer end of said anchor extending beyond the pivot and forming a hand grip.
2. A track lining device including a base,

a rail shifting lever fulcrumed on the base at one end thereof, and an anchor fulcrumed on the base at the same end thereof as the lever, said anchor extending beyond the pivot to form a hand grip.

3. A track lining device including a base, a rail shifting lever, an anchor cooperating with the base, and a common pivot for the lever and anchor carried by the base.

4. A track lining device including a base, a rail shifting lever fulcrumed at one end on said base and having the body portion thereof offset from said pivoted end, a ballast engaging anchor pivoted on said base independently of the rail shifting lever, said anchor being pivoted intermediate its ends and having one end curved downwardly and inwardly and the other end upwardly and outwardly.

5. A track lining device including a base having a pair of spaced bearing arms extend-

ing from one end thereof, a bearing pin mounted in said arms and having its ends projecting therebeyond, a rail shifting lever having one end disposed between said arms and fulcrumed on said pin, and an anchor fulcrumed on the outer ends of said pin.

6. A track lining device including a base having a pair of spaced bearing arms extending from one end thereof, a bearing pin mounted in said arms and having its ends projecting therebeyond, a rail shifting lever having one end disposed between said arms and fulcrumed on said pin, and an anchor fulcrumed on the outer ends of said pin, said anchor extending beyond its fulcrum to provide a rock arm having a lever-receiving socket formed therein.

In testimony whereof we hereunto affix our signatures.

CLARKSON A. DISBROW.

WILLIAM E. GADD.
